UNITED STATES PATENT OFFICE.

JOSEPH SILVERSTEIN, OF BROOKLYN, NEW YORK.

DESIGN FOR A CASING FOR DISINFECTOR.

Application filed November 13, 1923. Serial No. 7,755. Term of patent 3½ years.

To all whom it may concern:

Be it known that I, JOSEPH SILVERSTEIN, a citizen of the United States, residing in the borough of Brooklyn, county of Kings, State of New York, have invented a new, original, and ornamental Design for Casing for Disinfector, of which the following is a specification, reference being had to the accompanying drawing, forming part thereof.

Figure 1 is a front elevation of a casing for disinfector showing my new design.

Figure 2 is a side elevation thereof.

I claim:

The ornamental design for a casing for disinfector, as shown.

In testimony whereof, I have affixed my signature to this specification.

JOSEPH SILVERSTEIN.
